UNITED STATES PATENT OFFICE.

GEORGE D. SHIELDS, OF LOS ANGELES, CALIFORNIA.

CAST DRILL BIT WITH SPLIT-TANG ELEMENT.

Application filed April 2, 1927. Serial No. 180,429.

As may be inferred from the above title, it is an object of this invention to provide means for securing a hard blade or blades, such as may be formed by casting or by the subdivision or grinding of a flat stock, for rotation by a drill string, or the like; and in preference to welding a threaded tang element onto a suitable blade or body, or providing a one-piece tang element with 10 means for its reliable retention upon a shank integral with a drill blade or body, I herein propose to employ a two-piece or other split tang element,—relying either upon means such as a removable collar or upon an interiorly threaded element, such as a tang-receiving "box", or upon both, to hold the mentioned parts in their assembled relationships.

Other objects of my invention, in which I 20 may employ either suitably ground sections of flat stock (in the case of fish-tail bits) or one-piece castings, from a hard metal such as a manganese steel, or the like, and in which (always providing a shank integrally or otherwise rigidly connected with blade sections) I provide for a downward circulation of lubricating liquid either externally of said shank or therethrough, may be best appreciated from the following description of illustrative embodiments of my invention taken in connection with the appended claims and accompanying drawings, in which

Fig. 1 may be referred to as an elevational view, showing an embodiment of my invention comprising a blade of fish-tail type,—such as may be formed by casting or by suitably grinding a section of flat stock, too hard for convenient machining, to provide a shank integral with a blade.

Fig. 2 is a vertical sectional view taken substantially as indicated by the line 2—2 of Fig. 1, but showing also the lower end of a "box" or interiorly threaded retaining element hereinafter referred to as serving both for a securing and a rotating effect.

Fig. 3 is a horizontal sectional view, taken substantially as indicated by the line 3—3 of Fig. 1.

Fig. 4 is a sectional view, comparable with Fig. 3 but showing a feature of modification hereinafter referred to.

Fig. 5 is an elevational view comparable with Fig. 1, but showing an alternative

form embodying a "star" blade cast integral with a hollow shank.

Fig. 6 is a horizontal section, taken substantially as indicated by the line 6—6 of Fig. 5.

Fig. 7 is a perspective view, showing more particularly the relationships between a hollow shank and the blade sections of a "star" blade,—parts being broken away.

Fig. 8 is a perspective view showing one complete section of a two-piece tang element, 65 adapted to cooperate with a like tang element in the securing of a cast or other blade, having a suitable shank, at the lower end of a drill string (or to any suitable rotary element) provided with a "box" or female 70 retaining element adapted to hold said tank sections in assembled relationship.

Referring first to the details of that specific embodiment of my invention illustrated in Figs. 1, 2 and 3, I show a fish-tail 75 blade 11, such as may be formed by suitably grinding a section of flat bar stock, as having an enlargement 13, at or near its upper end,—the enlargement referred to being provided with beveled surfaces 14, 14', which 80 have an inward inclination adapting the same effectively to contact with correspondingly inclined surfaces, 15 (shown as conical) provided in the upper ends of tang sections 16, 16'.

The tang sections 16, 16' are shown as integral with body sections 17, 17' and as provided not only with "pin" threads 18 upon semi-frusto-conical positions thereof but with additional threads 19, in a central 85 region, intermediate between said frusto conical portions and said body portions,—said central region being adapted to carry a locking band or ring 20.

In case the locking element 20 is retained, 95 as above implied, by a threaded engagement, I consider it best not only to adapt the same to engage threads distinct from those provided upon the "pin" portions of the respective tang sections but also to employ left-hand threads at 19; but it should be understood that, depending upon the materials and the use intended, the locking element 20 may either be secured in an alternative manner or entirely omitted,—reliance being 100 then placed upon engagement between the two-part tang element and any "box", or the like, in which the same may be received, to

retain the mentioned parts in their assembled relationship,—the body sections 17, 17' being shown as respectively provided with deep notches 21, 21', suitably shaped to 5 interfit with and to impart rotation to the blade 11, by engagement with horizontal or other shoulders 22, 22', provided thereon.

In order to provide for a downward circulation of a suitable lubricating liquid, 10 instead of providing an interior passage through the shank 12, or its equivalent, I may form suitable vertical passages externally thereof as by cutting away respective tang sections 16^b, 16^a substantially 15 as shown at 23^a, 23^a', Fig. 4,—a locking ring 20^a being optionally provided thereon and the shank 12^a being shown as entirely rectangular. The shanks 12 and 12^a are shown as adapted closely to interfit within 20 vertical grooves 25, 25', provided in the sections 16, 16', or in corresponding grooves 25^a, 25^a', provided in the tang sections 16^a, 16^a'; but I may provide in 16, 16' or in 16^a, 16^a' additional vertical channels such as are 25 indicated at 24, 24' in Figs. 1 to 3 inclusive; or, as indicated in the figures last referred to I may rely, for circulation purposes, partially upon channels 23, 23', cut from the tang sections 16, 16' and partially 30 upon supplemental channels 24, 24' cut in the shank 12 and/or the blade 11.

Consistently with the foregoing, I show in Figs. 5-8 an alternative form in which a star blade comprising sections 11^b, integral with 35 a hollow shank 12^b (upwardly terminating in an enlargement 13^b) is provided with a 2-part tang element comprising sections 16^b and 16^a',—no locking ring being employed therewith. In this embodiment of my invention, dispensing with all effort to provide a wedge-fit between correspondingly inclined surfaces (such as the mentioned surfaces 14, 14', and 15, 15'), I employ substantially flat shoulders 14^a, 14^a' in engagement with oppositely disposed surfaces 15^a, 15^a', to prevent longitudinal movement of the tang sections 16^b, 16^a' relatively to the shank 12^b; and I show the shank 12^b as not only cylindrical in form to adapt the same 45 for engagement by correspondingly curved surfaces 25^b, within the respective tang sections, but as provided with a longitudinal passage 23^b, downwardly terminating in separate openings, 24^b, for the delivery of a lubricating liquid; and, in this form of my invention, each of the mentioned tang sections may be provided with a body portion 17^b, 17^a', having not only an intermediate notch or notches 21^b but also two half- 50 notches 21^a',—mating half-notches being adapted to cooperate in the engagement of alternate blade sections comprising shoulders 22^b, disposed therebetween; and the described parts may be held in their assembled relationship, pending the insertion of

the described sectional "pin" within a suitable "box" provided on a rotatable element, by means such as a mere wire 20^b,—shown as disposed in an out-of-the-way position below the threads 18^b, 18^a.

In all forms of my present invention, it will be seen that the respective tang sections 16, 16' (or 16^a, 16^a', 16^b, 16^b') are provided with oppositely disposed, flat longitudinal faces 26, (26^a, 26^b) in radial planes; and whether or not annular means (such as the locking-element 20 or a drive collar 20^a or the mere wire 20^b) are employed, reliance may be entirely or largely placed upon the clamping effect of a suitable interiorly threaded box 27, or its equivalent (see Fig. 2 only) to hold the mentioned tang sections together, and rigidly to retain blade sections therebetween, during the rotation of the entire organization, for a drilling effect.

Although I have described by present invention with particular reference to a well drilling bit, it will be understood that the principles thereof are believed to be of somewhat general application to all kinds of tools, as providing means for the securing of cast blades, too hard to be conveniently machined, with a machined tang, suitable for use in imparting rotation thereto; and it should be understood also that various features of my invention might be independently employed, and that numerous modifications additional to those herein suggested might easily be devised by workers skilled in the arts to which this case relates, without the slightest departure from the spirit and scope of my invention, as the same is indicated above and in the following claims.

I claim as my invention:

1. In a drill bit: a blade formed of material too hard for convenient machining and provided with a shank which has a terminal enlargement; and a sectional tang element provided with means for causing said blade to rotate therewith.

2. In a drill bit: a blade formed of a material too hard for convenient machining and provided with a shank which has a terminal enlargement; and a sectional tang element provided with threads and with means for securing said blade to rotate,—said last mentioned means comprising notched body portions integral with sections of said tang.

3. In a drill bit: a blade formed of a material too hard for convenient machining and provided with a shank which has a terminal enlargement; and a sectional tang element provided with threads and with means for securing said blade to rotate,—annular means being provided, below threads on said tang sections, to hold said sections in assembled relationship.

4. In a drill bit: a blade formed of a material too hard for convenient machining and

provided with a shank which has a terminal enlargement; and a sectional tang element provided with threads and with means for securing said blade to rotate,—an intermediate portion of each tang section being provided with additional threads for the reception of a locking-element; and an annular locking-element thereon.

5. In a drill bit: a blade formed of a material too hard for convenient machining and provided with a shank which has a terminal enlargement; and a sectional tang element provided with means for said blade to rotate,—the respective sections of said tang being provided with means permitting a downward circulation of a lubricating liquid therethrough.

6. In a drill bit: a blade formed of a material too hard for convenient machining and provided with a shank which has a terminal enlargement; and a sectional tang element provided with threads and with means for securing said blade to rotate,—said shank being provided with means permitting a downward circulation of a lubricating liquid externally thereof.

7. In a drill bit: a blade formed of a material too hard for convenient machining and provided with a shank which has a terminal

enlargement; and a sectional tang element, 30 provided with threads and with means for causing said blade to rotate,—said bit being provided with means for a downward circulation of a lubricating liquid.

8. In a drill bit: a blade formed of a material too hard for convenient machining and provided with a shank which has a terminal enlargement; and a sectional tang element provided with threads and with means for causing said blade to rotate,—the threads on 40 said tang being engageable by interior threads within a threaded “box”, for a locking effect.

9. In a drill bit: a blade formed of a material too hard for convenient machining and provided with a shank which has a terminal enlargement; and a sectional tang element provided with threads and with means for causing said blade to rotate,—the threads on 50 said tang being engageable by interior threads within a threaded “box”, for a locking effect; and additional annular means being provided to hold the mentioned parts assembled.

In testimony whereof, I have hereunto set 55 my hand at Los Angeles, California, this 19th day of March, 1927.

GEORGE D. SHIELDS.
